(57) CLAIM

The ornamental design for a cart, as shown and described.

DESCRIPTION

FIG. 1 is a front, top perspective view of a cart, showing my new design;

FIG. 2 is a rear, bottom perspective view thereof;

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof;

FIG. 8 is a bottom plan view thereof;

FIG. 9 is a front, top perspective view of the cart in another configuration;

FIG. 10 is a rear, bottom perspective view of the cart in another configuration;

FIG. 11 is an enlarged view of the area labeled 11 in FIG. 1; and,

FIG. 12 is an enlarged view of the area labeled 12 in FIG. 2.

The broken lines show portions of the cart that form no part of the claimed design.

The dot-dash-dot broken lines of the cart in FIG. 1 illustrate a boundary and cut line of the enlarged view in FIG. 11 and form no part of the claimed design.

The dot-dash-dot broken lines of the cart in FIG. 2 illustrate a boundary and cut line of the enlarged view in FIG. 12 and form no part of the claimed design.

1 Claim, 12 Drawing Sheets
